LOOM SELVAGE APPARATUS

Andrew J. Roper, James C. McCall, and Benjamin F. Underwood, Piedmont, S. C.

Application December 20, 1938, Serial No. 246,858

9 Claims. (Cl. 139—195)

This invention relates to a loom selvage apparatus which is capable of reinforcing the selvage ends of the warp while the filling is being projected through the shed so as to construct a cloth having the same appearance throughout. In many types of cloth it is very desirable to have the selvage warp ends of the same density as the ends throughout the intermediate portion of the cloth. This is particularly desirable where the cloth or fabric is to be subsequently coated as in the case of rubberized goods. In conventional weaving suitable right and left hand temples are used for the purpose of engaging the selvages of the cloth while the filling is placed therein. It is also customary to place the selvage ends closer together than the intermediate ends in order to provide a stronger area near the edge of the cloth to counteract the force applied thereto by the weft end.

It is an object of this invention to provide a loom selvage device which may be employed on either the right or left hand temples for reinforcing the selvage warp ends while the filling is being placed therebetween. By providing this reinforcing device, it is not necessary to make the warp ends near the selvage of any greater density than at the other points; consequently, the fabric, after it has been woven, will have the same appearance at the edge as it has in the center.

It is a further object of this invention to provide an apparatus for holding the selvage thread in a loom during the pick, comprising a temple head having a shank projecting downwardly therefrom and engageable by the lay of the loom upon the beat up stroke, a comb member pivoted on the said shank and having a cam surface, adjacent its pivot point projecting into the path of the lay and spring pressed means for normally forcing said comb into engagement with the selvage warp ends thereby the selvage warp ends will be reinforced while the shuttle is inserting the filling within the warp shed and whereby the comb will be removed from the selvage upon the beat up stroke of the lay.

By the use of this apparatus, double width cloth can be woven in a loom without leaving any tell-tale markings in the center of the double width cloth after the cloth has undergone a finishing operation.

Some of the objects of the invention having been stated other objects will appear as the description proceeds when taken in connection with the accompanying drawing, in which—

Figure 1 is a transverse sectional view through a portion of a loom showing the improved device mounted on a loom temple;

Figure 2 is a plan view taken along the line 2—2 in Figure 1;

Figure 3 is an isometric view of the improved loom selvage device;

Figure 4 is a vertical sectional view taken along the line 4—4 in Figure 1.

Referring more specifically to the drawing, the numeral 10 denotes the stationary or slide portion of the loom temple which has slidably mounted therein, shank 11. This shank has integral therewith a temple head 12, said temple head having rotatably mounted therein, a gripping roller 14 as at 15. This gripping roller is adapted to engage the selvage of the cloth immediately after it is being woven. The cloth is formed in the conventional manner by a plurality of warp ends 16 and a filling thread 17 which thread is carried back and forth through the shed in a conventional manner.

A lay 18 is also provided which has a reed 19 mounted therein between which the warp ends 16 are adapted to pass. In Figure 1 the bold line position of the lay indicates the position which is occupied when the shuttle passes through the warp thread. The dotted line position indicates that position that the lay occupies upon the beat up stroke at the time the shuttles are disposed in the shuttle boxes at opposed ends of the lay.

As heretofore stated, it is desirable in many instances to produce a fabric which is uniform throughout and in order to do so it is necessary to reinforce the selvage ends 16 so that the tension of the filling thread 17 will not have a tendency to narrow the cloth or to produce an excess strain upon the selvage ends. In order to do this, a suitable comb 22 has been provided, said comb having a plurality of teeth 23 extending downwardly therefrom. This comb is insertable within U-shaped member 24 and after it has been inserted a bolt 25 is tightened to lock the comb in position. The U-shaped member 24 is integral with a laterally projecting arm 25, said arm having slots 26 therein which slots are penetrated by screws 27. These screws have their other ends threadably embedded in an arm or bracket 28, and this arm projects forwardly and then downwardly (Figures 1 and 2) and has a suitable hole 29 therein which is loosely penetrated by a bolt 30.

The bolt 30 is fixedly secured to a suitable lug 31 on downwardly extending lip or flange 32 of 55

the temple head. Although the bolt 30 is fixedly secured in this lug, the arm 28 is nevertheless mounted for oscillation therearound and a suitable spring 35 is provided for normally forcing the comb 23 into bold line position as shown in Figure 1 so that the selvage warp ends will be reinforced while the shuttle passes through the warp shed. Torsion spring 35 has one end thereof penetrating the head of bolt 30 as at 37 and its other end 10 engaging the front of arm 29 as at 38.

Also it will be noted that the lower end of arm 28 has integral therewith a cam surface or projection 40 which normally extends upwardly into the path of the lay 18. Upon the beat up stroke 15 of the lay, that is when the lay assumes the dotted line position as shown in Figure 1 the rear edge of this projection 40 is engaged which will rotate the comb 23 to dotted line position and thereby allow the filling end to be beat up to its 20 proper position to cause cloth to be formed. As the lay moves toward bold line position then the torsion spring 35 will force the comb 23 to an engaged position with the selvage to act as a reinforcing member.

25 It has been found necessary to cut the temple head 12 as at 12a to allow the proper clearance of the teeth of the comb when the lay beats up. It also allows the assembly to be more compact.

The purpose of providing the slots 26 and the 30 screws 27 is to allow the necessary adjustment of the position of the teeth of the comb 22.

In order to furnish a suitable limit or stop 35 against which the arm 28 may rest, while the lay is in beat up position, a fibrous or lint block 42 is secured to the side of member 11 by any suitable means such as screws 43. This stop does not interfere with the operation of the arm, but merely prevents the arm from being rotated too far in a clockwise manner should the beat-up 40 stroke of the lay furnish an excessive impact to the comb supporting arm 28.

It is, therefore, seen that we have provided a simple loom selvage apparatus which is operable upon each beat up stroke of the lay and which 45 will reinforce the selvage ends of the cloth in such a manner that it will not be necessary to make the selvage warp ends more numerous than at other points.

In the drawing and specification there has been 50 set forth a preferred embodiment of the invention and although specific terms are employed, they are used in a generic and descriptive sense only, and not for purposes of limitation the scope of the invention being set forth in the appended claims.

55 We claim:

1. In a loom having a lay, a temple near each end of the lay, a slide for each temple, a downwardly projecting portion on the temple adapted to be engaged by the lay upon its oscillations to 60 move the temples in their slides, a selvage loop retainer having its lower end pivoted on said downwardly projecting portion and extending in front of the temple and over the temple and having a comb mounted in its free end disposed in 65 substantial alinement with the filling thread last woven in the loom, spring means normally moving said selvage loop retainer to cause the lower ends of the teeth of the comb to pass between the warp threads in the loom, said selvage loop retainer 70 having a portion on its lower end projecting rearwardly of the downwardly projecting portion of the temple, and upwardly from the pivot point, to be engaged by the lay before engagement of said downwardly projecting portion by the lay, where- 75 by the comb will be raised out of contact with

the warp threads for the passage of a filling thread being beat up and upon oscillatory movement of the lay away from the temple the comb will pass between the selvage warp threads and retain them in position against the pull of the filling thread being woven in the warp threads. 5

2. In a loom having a lay, a temple near each end of the lay, a slide for each temple, a downwardly projecting portion on the temple adapted to be engaged by the lay upon its oscillations to 10 move the temples in their slides, a selvage loop retainer having its lower end pivoted on said downwardly projecting portion and extending in front of the temple and over the temple and having a comb mounted in its free end disposed in substantial alinement with the filling thread last woven in the loom, spring means normally moving said selvage loop retainer to cause the lower ends of the teeth of the comb to pass between the warp threads in the loom, said selvage loop retainer having a portion on its lower end projecting rearwardly of the downwardly projecting portion of the temple and upwardly from the pivot point to be engaged by the lay before engagement of said downwardly projecting portion by the lay, whereby the comb will be raised out of contact with the warp threads for the passage of a filling thread being beat up and upon oscillatory movement of the lay away from the temple the comb will pass between the selvage warp threads and retain them in position against the pull of the filling thread being woven in the warp threads, and means limiting upward movement 20 of the comb. 25

3. A selvage forming device for a loom, comprising a bracket having its lower end pivoted to the flange of the temple which is engaged by the oscillating lay of the loom and having a portion projecting upwardly and rearwardly of the flange 40 so that the bracket will be engaged and moved on its pivot before engagement of the flange by the lay of the loom, said bracket extending upwardly on the side of the temple remote from the lay and projecting forwardly over the temple, a member adjustably secured to the free end of said bracket, a comb having a plurality of teeth therein whose free lower ends are pointed, means for removably securing the comb in the outer free end of said member, spring means normally urging said bracket to swing on its pivot to lower the comb to occupy a position between the warp threads in the loom, whereby engagement by the lay of the portion of the bracket projecting rearwardly of the flange will swing said bracket 45 against its spring means and thus move the comb to cause its teeth to pass upwardly from between the warp threads to allow a beat up and upon reverse oscillation of the lay the comb on account of its spring means will move between the warp threads in close proximity to the fell of the cloth while the filling thread is passed towards the other side of the loom. 50

4. A selvage forming device for a loom, comprising a bracket having its lower end pivoted to the flange of the temple which is engaged by the oscillating lay of the loom and having a portion projecting upwardly and rearwardly of the flange so that the bracket will be engaged and moved on its pivot before engagement of the flange by 7 the lay of the loom, said bracket extending upwardly on the side of the temple remote from the lay and projecting rearwardly over the temple, a member adjustably secured to the free end of said bracket, a comb having a plurality of 7

teeth therein whose free lower ends are pointed, means for removably securing the comb in the outer free end of said member, spring means normally urging said bracket to swing on its pivot to lower the comb to occupy a position between the warp threads in the loom, whereby engagement by the lay of the portion of the bracket projecting rearwardly of the flange will swing said bracket against its spring means and thus move the comb to cause its teeth to pass upwardly from between the warp threads to allow a beat-up and upon reverse oscillation of the lay the comb on account of its spring means will move between the warp threads in close proximity to the fell of the cloth, while the filling thread is passed towards the other side of the loom, and stop means for limiting swinging movement of the bracket under the urging of its spring.

20 5. In a loom temple having a downwardly projecting flange engageable by the lay of the loom, a selvage loop retainer having its lower end pivoted forwardly of said flange and having a portion projecting above and rearwardly of said pivot point to a point located rearwardly of the surface of the flange which is disposed next to the lay of the loom, said loop retainer extending upwardly on the side of the temple remote from the lay and then rearwardly extending over the top of the temple, and a comb adjustably secured to the free end of the loop retainer and having a plurality of downwardly extending teeth therein for passing between the warp threads and holding the same against the tension of a filling thread thrown by the shuttle, whereby the selvage loop retainer will be moved by engagement with the lay before the lay engages the flange of the temple.

6. In a loom having a lay, a temple near each end of the lay, a slide for each temple, a downwardly projecting portion on the temple adapted to be engaged by the lay upon its oscillations to move the temples in their slides, a selvage loop retainer having its lower end pivoted adjacent the front surface of said downwardly projecting portion and extending upwardly adjacent the front side of the temple, and over the temple, and having a comb mounted in its free end disposed in substantial alinement with the filling thread last woven in the loom, spring means normally moving said selvage loop retainer to cause the lower ends of the teeth of the comb to pass between the warp threads in the loom, said selvage loop retainer having a portion on its lower end projecting rearwardly of the downwardly projecting portion of the temple, and upwardly from the pivot point, to be engaged by the lay before engagement of said downwardly projecting portion by the lay, whereby the comb will be raised out of contact with the warp threads for the passage of a filling thread being beat up and, upon oscillatory movement of the lay away from the temple, the comb will pass between the selvage warp threads and retain them in position against the pull of the filling thread being woven in the warp threads.

7. A loom having a lay, a temple near each end of the lay, a slide for each temple, a downwardly projecting portion on the temple adapted to be engaged by the lay upon its oscillation to move the temples in their slides, a selvage loop retainer having its lower end pivoted adjacent the front surface of said downwardly projecting portion and extending upwardly adjacent the

front side of the temple, and over the temple and having a comb mounted in its free end disposed in substantial alinement with the filling thread last woven in the loom, spring means normally moving said selvage loop retainer to cause the lower ends of the teeth of the comb to pass between the warp threads in the loom, said selvage loop retainer having a portion on its lower end projecting rearwardly of the downwardly projecting portion of the temple and upwardly from the pivot point to be engaged by the lay before engagement of said downwardly projecting portion by the lay, whereby the comb will be raised out of contact with the warp threads for the passage of a filling thread being beat up and upon oscillatory movement of the lay away from the temple the comb will pass between the selvage warp threads and retain them in position against the pull of the filling thread being woven in the warp threads, and means limiting upward movement of the comb.

8. A selvage forming device for looms comprising a bracket having its lower end pivoted to move with the temple of the loom, said pivot being adjacent the front surface of the flange of the temple which is engaged by the oscillating lay of the loom, said selvage forming device having a portion projecting upwardly and rearwardly of the flange so that the bracket will be engaged and moved on its pivot before engagement of the flange by the lay of the loom, said bracket extending upwardly on the side of the temple remote from the lay and projecting forwardly over the temple, a member adjustably secured to the free end of said bracket, a comb having a plurality of teeth therein whose free lower ends are pointed, means for removably securing the comb in the outer free end of said member, spring means normally urging said bracket to swing on its pivot to lower the comb to occupy a position between the warp threads in the loom, whereby engagement by the lay of the portion of the bracket projecting rearwardly of the flange will swing said bracket against its spring means and thus move the comb to cause its teeth to pass upwardly from between the warp threads to allow a beat up and upon reverse oscillation of the lay, the comb, on account of its spring means, will move between the warp threads in close proximity to the fell of the cloth while the filling thread is passed towards the other side of the loom.

9. A selvage forming device for looms comprising a bracket having its lower end pivoted adjacent the front surface of the flange of the temple which is engaged by the oscillating lay of the loom, and having a portion projecting upwardly and rearwardly of the flange so that the bracket will be engaged and moved on its pivot before engagement of the flange by the lay of the loom, said bracket extending upwardly on the side of the temple remote from the lay and projecting rearwardly over the temple, a member adjustably secured to the free end of said bracket, a comb having a plurality of teeth therein whose free lower ends are pointed, means for removably securing the comb in the outer free end of said member, spring means normally urging said bracket to swing on its pivot to lower the comb to occupy a position between the warp threads in the loom, whereby engagement by the lay of the portion of the bracket projecting rearwardly of the flange will swing said bracket against its

- spring means and thus move the comb to cause its teeth to pass upwardly from between the warp threads to allow a beat-up and upon reverse oscillation of the lay the comb on account of its 5 spring means will move between the warp threads in close proximity to the fell of the cloth, while the filling thread is passed towards the other side of the loom, and stop means for limiting swing-

ing movement of the bracket under the urging of its spring.
